COMBINATION VENDOR AND DISPLAY CASE FOR GENERAL MERCHANDISE

Walter E. Moore, Bel-Nor, and Harry H. Pryor, St. Louis,
Mo., assignors to National Vendors, Inc., St. Louis,
Mo., a corporation of Missouri

Filed June 3, 1960, Ser. No. 60,839

Term of patent 14 years

(Cl. D52—3)

FIG. 1.

FIG. 2.

FIG. 4.

FIG. 3.

FIG. 5.

FIG. 1 is a perspective view of a combination vendor and display case for general merchandise showing our new design;

FIG. 2 is a top plan view of FIG. 1;

FIG. 3 is a right side elevation of FIG. 1;

FIG. 4 is a rear elevation of FIG. 1; and

FIG. 5 is an enlarged fragment of FIG. 1 in elevation.

We claim:

The ornamental design for a combination vendor and display case for general merchandise, substantially as shown.
